CLAIM

The ornamental design for clip for supporting medical devices or the like on a support rail, as shown and described.

DESCRIPTION

FIG. 1 is a perspective view of the clip for supporting medical devices or the like on a support rail showing my new design;

FIG. 2 is a cross-sectional view thereof taken along line 2—2 in FIG. 1;

FIG. 3 is a side elevational view thereof;

FIG. 4 is a bottom plan view thereof;

FIG. 5 is a rear elevational view thereof;

FIG. 6 is an opposite side elevational view thereof;

FIG. 7 is a top plan view thereof.

FIG. 1

FIG. 2

FIG. 3

FIG. 4

FIG. 5

FIG. 6

FIG. 7
